CLAIM

The ornamental design for a humidifier, as shown and described.

DESCRIPTION

FIG. 1 is a first perspective view of the humidifier showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof;

FIG. 9 is a cross-sectional view thereof taken along 9-9 of FIG. 6; and,

FIG. 10 is a cross sectional view thereof taken along line 10-10 of FIG. 6.

The dash-dot-dash broken lines immediately adjacent the shaded areas represent the bounds of the claimed design while all other broken lines are directed to portions of the humidifier. The broken lines form no part of the claimed design.

1 Claim, 9 Drawing Sheets
